UNITED STATES PATENT OFFICE.

CHARLES H. BOECK, OF JACKSON, MICHIGAN, ASSIGNOR TO THE CENTRAL
OILGAS STOVE COMPANY, OF FLORENCE, MASSACHUSETTS.

DESIGN FOR AN OIL OR GAS STOVE.

SPECIFICATION forming part of Design No. 21,365, dated March 8, 1892.

Application filed January 11, 1891. Serial No. 417,737. Term of patent 14 years.

To all whom it may concern:

Be it known that I, CHARLES H. BOECK, a citizen of the United States, residing at Jackson, in the county of Jackson and State of Michigan, have invented and produced a new and original Design for Oil and Gas Stoves, of which the following is a full, clear, and exact specification.

My design relates to an oil or gas stove; and it consists of a rectangular base having an arched frame surmounting the same, with a globe having an ornamented crown-piece interposed between the uprights and the frame.

In the accompanying drawing the design is represented in perspective.

The stove-base is of rectangular shape, and

the frame surmounting it comprises round uprights or posts and an arched piece connecting the uprights. The shade of spherical form is located upon the base and between the uprights, and surmounting the shade is a crown-piece having a flaring top and laterally-projecting flanges. 20

I claim—

The design for an oil or gas stove, herein shown and described. 25

In testimony whereof I affix my signature in presence of two witnesses.

CHARLES H. BOECK.

Witnesses:

THOMAS A. WILSON,
W. S. COBB.
